CLAIM

The ornamental design for a box container, as shown and described.

DESCRIPTION

FIG. 1 is a front isometric view of a box container, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a front isometric view thereof, in a condition of use;

FIG. 9 is a top view thereof;

FIG. 10 is a left side view thereof;

FIG. 11 is another isometric view thereof, in a condition of use; and,

FIG. 12 is a right side view thereof.

The broken lines depict portions of the article and environment that form no part of the claimed design.

1 Claim, 10 Drawing Sheets
